UNITED STATES PATENT OFFICE.

ISADORE TORNANSKY, OF ELLINGTON, CONNECTICUT.

COMBINATION TOILET ARTICLE.

1,405,077.

Specification of Letters Patent. Patented Jan. 31, 1922.

Application filed October 26, 1921. Serial No. 510,602.

To all whom it may concern:

Be it known that I, ISADORE TORNANSKY, a citizen of the United States, residing at Ellington, in the county of Tolland and 5 State of Connecticut, have invented certain new and useful Improvements in Combination Toilet Articles, of which the following is a specification.

This invention relates to combination 10 toilet articles and more particularly to a combination hair brush, mirror, comb cleaner and hair pin holder.

The primary object of the invention is to provide a combination toilet article in which 15 the different elements will be combined in a neat and efficient manner and which may be easily moved into operative position for using them in the manner desired.

Another object of the invention is to provide 20 an article of this character which will have a neat appearance and which will have the general proportion and appearance of an ordinary hair brush but which will combine the additional elements of a mirror, 25 comb cleaner and hair pin holder in a manner that will not require any material change in the general size and construction of the article.

Other objects of the invention will appear 30 upon consideration of the following detail description and accompanying drawings wherein:—

Figure 1 is a plan view of the device constructed in accordance with my invention,

35 Figure 2 is a side elevation,

Figure 3 is a longitudinal section,

Figure 4 is a transverse section,

40 Figure 5 is a top plan view showing the mirror and comb cleaner in operative position,

Figure 6 is a detail view of the comb cleaner, and

Figure 7 is a cross section through the hair pin holder.

45 Referring to the drawing by numerals, the body 1 of the brush is provided with the brush bristles 2 which project from one face of the body, and the body is provided with the handle 3 of the usual formation, but the 50 handle is equipped with a longitudinal cylindrical recess 4, long enough to receive a quantity of hair pins and having one end open at the end of the handle, the open end being adapted to be closed by a removable cap member 5. This recess 4 forms a con-

venient receptacle for holding the pins and hair pins.

The place in the brush opposite the bristles 2 is provided with a rectangular recess 6 which forms a compartment to receive a 60 comb cleaner 7 which is shown in detail in Figs. 5 and 6 in the drawing. This comb cleaner includes end bars 8 and 9, the latter being relatively short in length as compared to the clip 8 and the strip 9 is hingedly connected as indicated at 10 to one end of the brush body so that the comb cleaner may be swung out to the position shown in Fig. 5 of the drawing. Strips 9 and 8 are connected by strands of any suitable material which 70 are spaced relatively close together so that they may be inserted between the teeth of the comb. The brace 7' is to give rigidity to the cleaner when in use.

When the comb is mounted upon the cleaner 75 by passing the strands 10 between the teeth of the comb, the comb may be longitudinally reciprocated and the strands will thoroughly clean the comb and remove any foreign material therefrom. When the comb cleaner 80 is not in use it may be folded back into the compartment 6. Hinged legs 8' serve to hold cleaner at an angle. The compartment 6 is closed by the mirror 11 which consists of a rectangular plate finished with nickel 85 to give it the reflecting qualities, and it will be understood that a glass mirror may be provided if desired, this being one of the variations which may be included in the invention. The mirror is provided with an 90 extension 12, pivotally mounted upon the handle by a pivot member 13 whereby the mirror may be swung to the position shown in Fig. 5 of the drawing when it is in use. This will permit the compartment 6 to be 95 opened, whereby the comb cleaner may be thrown into operative position.

It will be noted from the above, that the various elements included in the invention are compact and arranged in a neat manner 100 so that the brush will have a neat appearance and will not be cumbersome or large in its proportions.

Minor changes may be made in the details of construction without departing from 105 the spirit of the invention or the scope of the claims hereunto appended.

What is claimed is:—

1. An implement of the character described comprising a brush body provided 110

on one side with brush bristles, a compartment mounted on the opposite side of the brush body, a comb cleaner including two strips arranged within the compartment 5 and equipped with longitudinal strands connecting the two strips together, one of the strips being hingedly connected to one end of the brush body whereby the comb cleaner may be swung into and out of the 10 compartment in the brush body.

2. In an implement of the character described, the combination of a brush body provided on one side with brush bristles, the opposite side of the brush body being provided with a compartment, a comb cleaner including a pair of elongated strips mounted in the compartments, one of the strips being hingedly connected to the brush body, flexible strands connecting the said strips, 15 and a mirror pivotally mounted upon the brush body and adapted to normally fit over the said compartment to cover the said comb cleaner.

3. In an implement of the character de-

scribed, the combination of a brush body 25 provided on one side with brush bristles, the opposite side of the brush body being provided with a compartment, a comb cleaner including a pair of elongated strips mounted in the compartments, one of the 30 strips being hingedly connected to the brush body, flexible strands connecting the said strips, and a mirror pivotally mounted upon the brush body and adapted to normally fit over the said compartment, to cover the said comb cleaner, the said brush body being equipped with a handle, the said mirror having an extension pivotally connected to the handle, the said handle having an elongated recess forming a receptacle and means to 40 close the open end of the receptacle.

In testimony whereof, I have affixed my signature in the presence of two witnesses.

ISADORE TORNANSKY.
